DUAL PACK-OFF SOCKET

Daniel D. Pilgrim and John J. Meagher,
Bakersfield, Calif.

Application June 20, 1947, Serial No. 756,066

2 Claims. (Cl. 294—102)

1

This invention relates to a dual pack-off socket for use in recovering broken sections of pipe in an oil well, or the like.

An object of our invention is to provide a novel fishing tool of the pack-off socket type in which both the inside and the outside of the lost or broken pipe is packed-off when engaged by the tool.

A feature of our invention is to thus provide a means whereby fluid circulation can be forced into the lost or broken section of the pipe, which is important in loosening the pipe so that it may be removed to the surface.

Another object of our invention is to provide a novel dual pack-off socket in which the slip hanger is so constructed that it will engage the top of the lost section of pipe, and thereby permit control of the slip hanger so that it may be released to permit the slips to drop downwardly, and press inwardly against the lost pipe.

Another feature of our invention is to provide a dual pack-off socket in which the internal and external members are run simultaneously with the gripping or fishing portion of the tool, thus permitting a circulation of fluid into the lost section of the pipe at the same time that pipe is gripped, and a strain is placed upon the pipe prior to its removal from the well.

Other objects, advantages and features of invention may appear from the accompanying drawing, the subjoined detailed description and the appended claims.

In the drawing:

Figure 1 is a longitudinal sectional view of our dual pack-off socket.

Figure 2 is a fragmentary side elevation of the head or coupling.

Figure 3 is an enlarged bottom plan view of the slip hanger.

Referring more particularly to the drawing, the numeral 1 indicates a head or coupling member, into which or on to which the drill pipe is threaded, and the threads for the drill pipe are shown at 2. A sleeve 3 screws on to the head 1 and this sleeve is provided with a tapered seat 4, at its lower end, and the purpose of this seat will be further described. The head 1 is provided with one or more bayonet slots 5, and these bayonet slots are used to control the slip hanger 6. The slip hanger is provided with pins 7 which project outwardly into the bayonet slots 5. A plurality of slips 8 depend from the slip hanger 6 and are supported on this slip hanger. The slips are tapered on their lower ends as shown at 9, and when this tapered portion of the slip engages

2

the seat 4, the slips will be forced inwardly, to grip the lost section of pipe 10.

In the drawing, the upper part of the pipe 10 is shown in dotted lines, the purpose of this being to clarify the drawing, in that if the pipe 10 were shown solid, it would hide a portion of the slips 8. When the tool is lowered into the well, the pipe 10 will slide into the tool until it strikes the bottom of the slip hanger 6.

10 A plurality of radial teeth 11 are formed on the bottom of the slip hanger and these teeth will engage the top of the pipe 10, thus holding the slip hanger 6 against rotation and enabling the head 1 to be rotated relative to the slip hanger, thereby moving the pin 7 into the vertical portion of the bayonet slots 5. When the pins are in this vertical portion of the bayonet slot, the entire assembly of slip hanger and slips can drop downwardly so that the lower portion of the 15 slips will engage the seat 4, thus pressing these slips inwardly against the lost pipe or fish 10.

A spring 12 engages the slip hanger 6 to urge this slip hanger downwardly. A tube 13 screws in to the head 1, that is, into the bore 14 of the 20 head and a packing or cup rubber 15 is mounted on the lower end of the tube. This packing or cup engages the inner wall of the pipe 10, and the cup is expanded by fluid pressure, thus sealing the inside of the pipe 10, i. e., providing an 25 inside pack-off. Fluid, when forced through the drill pipe, and into our tool, flows through the tube 13 and thence downwardly into the fish 10. The outside of the fish 10 is also packed-off by the external packing ring 16, which is mounted 30 in the sub 17, which screws on to the bottom of the sleeve 3. It will thus be evident that we pack-off the fish on both the inside and the outside and fluid under pressure can thus be compelled to 35 flow around the bottom of the fish 10, thus loosening the formation around the fish, and enabling the same to be removed to the surface by the slip 8.

Having described our invention, we claim:

1. A dual pack-off socket, comprising a head, 45 a slip hanger mounted in the head, a sleeve depending from the head, a slip socket mounted in the head, latch means in the head engaged by the slip hanger, slips depending from the slip hanger, and teeth on the bottom surface of the 50 slip hanger adapted to engage the lost section of the pipe, whereby said slip hanger is held against rotation when said teeth engage the lost section of pipe, a pipe depending from said head, a packing mounted on the lower end of the pipe and engaging the inside of the lost pipe, and an 55

outside packing engaging the outside of the lost pipe, and means mounting said last named packing, said first and last named packings being in substantially the same horizontal plane.

2. A dual pack-off socket, comprising a head, 5 said head having a bayonet slot therein, a slip hanger, a pin projecting from the slip hanger into the bayonet slot, a sleeve depending from the head, slips depending from the slip hanger and arranged within the sleeve, teeth on the bottom 10 of the slip hanger, engageable with the top of a lost pipe section, thereby holding the slip hanger stationary relative to said head, a tube depending from the head and extending through the slip hanger, packing mounted on the lower end of the 15 tube and engaging the inside of the lost pipe, and an outside packing engaging the outside of the lost pipe, and means mounting said last named

packing on said sleeve, said first and last named packings being in substantially the same horizontal plane.
